BLANKET SPRAY NOZZLE

Raymond P. Paradise, Indianapolis, Ind.

Application July 15, 1940, Serial No. 345,461

5 Claims. (Cl. 299—153)

This invention relates to nozzles for projecting a liquid in a finely divided or atomized state in the form of a fan with a uniform state of dispersion across the projected spray and with a considerable depth.

The invention primarily consists of providing a slot-like orifice through a spherical cap wherein in the sides of the slot each slope toward the axis of the fluid flow, being further apart between their central parts than at the ends, and having lands between the terminal ends of the slot sides, these lands having faces perpendicular to the flow axis. The width of the spray and its diffusion may be controlled for any given fluid supply pressure by varying the width and length of the slot and by varying the angle of the slot sides.

One use of the invention has been found to be in insect control, since the high velocity of the spray exerts a washing effect.

Another use of the invention which is important is in fire extinguishing devices where, I have found, fires are quickly extinguished with a minimum amount of fluid by directing a flat, widespread mass of the extinguishing fluid across the zone of the fire, the fluid being in a sufficiently finely divided state as will permit the heat of the fire to quickly vaporize the fluid from the under side of the spray.

Generally the sprays heretofore provided have been conical in nature—either hollow or solid—and this has meant that the spray would either have to be directed into the fire in order to secure a sufficient width of spray, or if directed above the fire there would be a rounded under side which would permit the flame to travel upwardly therearound without any smothering or "blanketing off" action. A flat form of spray is most effective, but attempts heretofore to obtain it have not been successful in providing a spray having a uniform density across its width. The general difficulty has been that such a spray would give a heavy outer edge boundary with practically nothing in the center such as was visualized in the old type gas jets providing fish-tail flame. With such a type spray, there would not be sufficient density through the central portions to hold down the fire and prevent it from breaking through the spray.

My invention overcomes these difficulties by use of an extremely simple form of orifice, the invention being illustrated in one particular form in the accompanying drawing, in which

Fig. 1 is a side elevation of a nozzle incorporating the invention;

Fig. 2, a transverse section through the nozzle on the line 2—2 in Fig. 1;

Fig. 3, a section on line 3—3 in Fig. 2;

Fig. 4, a section on the line 4—4 in Fig. 2;

Fig. 5, a central section of the orifice plate showing a modified form of orifice end land; and

Fig. 6, a central section of the orifice plate showing a further modified form of orifice end land.

Like characters of reference indicate like parts throughout the several views in the drawing.

The essential feature of the invention is embodied in the orifice plate 10 which comprises a disc of metal having a convex spherical surface presented toward the on-coming fluid. This plate 10 is provided with a central orifice 11, the form of which will be hereinafter described.

The plate 10 is provided with an annular flange 12 to engage over the end of the nozzle pipe 13 and there be compressively secured by means of the retaining nut 14 which is provided with an inturned annular flange 15 extending over the flange 12. In order to secure a fluid tight joint between the plate 10 and the pipe 13, the diameter of the circle defined by the junction of the flange with the curved part of the plate on its inside face is made to be slightly greater than the internal diameter of the pipe 13 so that when the plate 10 is initially positioned over the end of the pipe 13, the flange 12 does not seat on the end of the pipe, but instead the inside corner of the pipe will strike the curved part of the plate.

Then as the nut 14 is drawn up tightly on the pipe 13, the plate 10 will be carried inwardly to eventually seat the flange 12 on the pipe end so as to force the curved portion of the plate within the pipe opening. This provides a very effective seal. The difference in diameters between the junction line above described and the pipe diameter is a matter of from five to ten thousandths of an inch depending, of course, upon the pipe diameter.

The plate 10 has an appreciable thickness, as the drawing indicates, and the orifice 11 is formed in any suitable manner such, for example, as by use of a milling cutter operated diametrically across the convex side of the plate.

There are three essential features involved in this orifice 11. First the orifice is of a "slit" type wider through its central portions than at its ends and the opposite sides of the slit are sloped at a suitable angle exceeding forty-five degrees, a sixty degree angle being preferable. Then the ends of the orifice do not terminate in lines but

have land portions 16 and 17 respectively, having

15

16

17

18

faces positioned at right angles to the flow axis of the nozzle. These lands or end zones are essential in order to provide a uniform distribution of the fluid throughout the transverse width of the fluid after it leaves the orifice. The sloped sides of the orifice and the tapered nature thereof provide the atomization of the fluid. The radius of curvature of the plate 10 will vary in accordance with the pressure of the fluid in the nozzle 13—the greater the pressure, the less degree of curvature employed. The width of the orifice 11 between the sloped sides may be varied in accordance with the volume of spray desired. The thickness of metal forming the plate 10 is made to be sufficient as will cause a directing action of the fluid as it passes through the orifice whereby the fluid striking the sloped edges will be directed toward the flow coming off of the opposite edge.

The general operation of the nozzle is represented in Figs. 3 and 4 wherein the spray is indicated as leaving the orifice in a diverging manner with a uniform distribution of the atomized particles of the fluid. Looking at the spray from the side, as indicated in Fig. 4, the spray has an appreciable thickness which increases with the distance from the orifice. Of course, the under side of the spray will tend to drop downwardly under the influence of gravity as the tiny drops settle in the nature of a fog.

As shown in Figs. 3 and 4, the lands 16 and 17 are flat surfaces in a common plane perpendicular to the central axis through the plate 10. This form of land is simple to form and is very effective. In Fig. 5 is shown a modified land 18 in that while all elements in its face are perpendicular to the direction of the plate axis, its face is curved between the ends of the side edges of the orifice 11. In Fig. 6, the land 19 is modified to have a V-shape, but the faces thereof still remain perpendicular to the direction of the plate 10 axis.

It is to be noted that the slot 11 is shaped to present major side walls whose faces decrease in angle with the flow axis from center to ends of the slot. The widths of the lands 16 and 17 are varied in accordance with the operating pressure and desired width of stream, while both the lands 16 and 17 and the angle of the side walls of the orifice are varied in accordance with the amount of fluid discharge required. By reason of the variation in any one nozzle of the slope of the side walls from the center to the ends thereof, the nozzle will operate at any pressure with uniform distribution of atomization across the entire width of the spray without either a splitting or "fishtail" effect, or with a heavy central converging flow with lighter boundary flow, as has been the difficulty in sprays from other shapes of orifices heretofore employed.

While I have herein shown and described my

invention in the one particular form, it is obvious that structural variations may be employed without departing from the spirit of the invention and I, therefore, do not desire to be limited to that precise form beyond the limitations as may be imposed by the following claims.

I claim:

1. In a nozzle for a blanket spray, an orifice plate having a spherically curved surface convexly presented toward the flow of fluid through the nozzle and having a slot through the plate centrally positioned thereacross, said slot being wider through its central portion than at its ends, said ends terminating in areas normal to the axis of said flow, said areas spacing apart the sides of said slot.

2. In a nozzle for a blanket spray, an orifice plate having a spherically curved surface convexly presented toward the flow of fluid through the nozzle and having a slot through the plate centrally positioned thereacross, said slot being wider through its central portion than at its ends, said ends terminating in areas normal to the axis of said flow, said areas spacing apart the sides of said slot, and said slot sides being of sufficient thickness and angularity as to direct flow of said fluid angularly from said nozzle flow, one side toward the other for atomization of the fluid.

3. An orifice plate for a nozzle having a portion convexly curved for presentation toward oncoming fluid and a central slot cut through the plate from the convex side to have that shape and form as would be cut by moving diametrically and transversely across the plate a rotary milling cutter with a cylindrical cutting peripheral edge bevelled equally on each side therefrom to cut an included angle of at least 60 degrees.

4. An orifice plate for a nozzle having a portion convexly curved for presentation toward oncoming fluid and a central slot cut through the plate from the convex side to have that shape and form as would be cut by a rotary milling cutter bevelled equally on each side to cut an included angle of at least 60 degrees, and moved diametrically and transversely across the plate.

5. In a nozzle, a substantially rigid orifice plate having a spherically curved central portion convexly presented inwardly of the nozzle, an outwardly flange about the plate, said nozzle having a plate receiving mouth into which the curved portion of the plate is inserted, the diameter of the junction line between said flange and said curved portion of the plate slightly exceeding that of said mouth, a flange abutting face around said mouth, and means carried by the nozzle to draw said plate flange against said face to force said plate curved portion into said mouth to effect a fluid seal between the periphery of said mouth and said plate curved portion.

RAYMOND P. PARADISE.
